UNITED STATES PATENT OFFICE

JOSEPH THOS. DAWICKI, JR., OF JERSEY CITY, NEW JERSEY

WINDOW FASTENER

Application filed June 5, 1931. Serial No. 542,404.

The present invention relates to new and useful improvements in builders' hardware, and more particularly it pertains to a new and improved form of window lock.

5 It is one of the objects of the present invention to provide a new and improved window lock which will securely hold two sliding sash members against movement relative to each other.

10 A further object of the invention resides in the provision of a device of the aforementioned character which will automatically move to open position from locked position when properly operated.

15 It is a further object of the invention to provide a window lock which will prevent operation to released position by the insertion of a tool between the meeting rails of a window sash.

20 With the above and other objects in view which will become apparent as the nature of the invention is better understood, reference will be had to the accompanying drawings, wherein:

25 Figure 1 is a transverse sectional view taken through the meeting rails of two window sash and showing a lock constructed in accordance with the present invention in its closed position,

30 Figure 2 is a horizontal sectional view showing the lock in section, and the meeting rails in top plan, and;

35 Figure 3 is a detail perspective view of the lock, the lock being shown in its released or open position.

Referring more particularly to the drawings, the reference characters 5 and 6 designate the meeting rails of an inner and outer window sash respectively.

40 A lock constructed in accordance with the present invention, preferably includes two housing members 7 and 8 which may be formed of any suitable material such as sheet metal and which are secured to the meeting rails of the outer and inner sash 6 and 5 respectively. The housings 7 and 8 are secured to their respective sash by means of screws or the like 9 which preferably pass through the housings near the ends thereof.

45 50 Pivots connected as at 10 to the housing

7, there is a swinging member 11 which member has a right angular extension 12 provided with a pair of spaced openings 13 as best illustrated in Figure 3. The pivotal point of the member 10 consists of a rod 14 mounted 55 in an opening 15 in the top wall of the housing 7 and surrounding the rod, and having one end 16 engaging the member 10 and the other end 17 engaging the housing, there is a coil spring 18 which tends to hold the 60 swinging member 10 in its upright or open position.

The housing 8 is provided in its upper wall with a slot or the like 20 which is adapted to receive the right angular extension 12 of 65 the member 10 when the latter is moved to its locking or closing position. As best illustrated in Figure 2, there are two guide rods 22 which extend transversely of the housing member 8 and slidably mounted on these guide 70 rods, there is a cross bar 23 the latter being provided with openings to receive the guide rods 22. This cross bar 23 carries a plurality of projecting lugs or the like 24 which are adapted to pass through the openings 13 here- 75 tofore mentioned when the swinging member 10 is moved to its locking position and these members also pass in the openings 25 in the front wall of the housing 8. A bowed spring 29 is employed for maintaining the 80 cross bar 23 in its forward or locking position, and an operating member in the form of a shaft 30 having an operating knob 31 is attached to the cross bar 23 and projects through an opening in the front wall of the 85 housing 8 to the exterior thereof.

From the foregoing it is apparent that with the parts in the position in which they are illustrated in Figure 3, it is only necessary to swing the member 10 about its pivotal point 90 against the action of the hinge 18 until the right angular extension 12 is positioned within the slot it being understood that the cross bar 23 will be depressed against the spring 29 to permit of this movement. After this has 95 been done the member 23 is released and the spring 29 forces the projecting lugs 24 into the opening 13 to lock the member in its closed position.

While the invention has been herein illus- 100

trated in a preferred form, it is to be understood that the same is not to be limited to the construction herein shown, and that it may be practiced in other forms without departing from the spirit thereof.

Having thus described the invention, what is claimed as new and what it is desired to secure by Letters-Patent of the United States, is:

- 10 A lock for windows comprising in combination with two window sash, a housing member carried by the meeting rail of each sash, a pivoted member carried by one of said housing members, a right angular extension on said pivoted member, said right angular extension having a plurality of openings therein, a slot in one of the walls of the other housing, said slot adapted to receive the right angular extension of the pivoted member, and means for engagement with the openings in the right angular extension of the pivoted member to lock it in the housing, said last mentioned means comprising a sliding bar, and a plurality of projections on said sliding bar for entrance into the openings of the pivoted member and openings in the side wall of the housing in which it is mounted, and a spring for moving said bar into locking position.
- 30 In testimony whereof I affix my signature.
JOSEPH THOS. DAWICKI, JR.
